DIVING BOARD

William J. Nightingale, Valparaiso, Ind., assignor
to Sterling Manufacturing Company, Val-
paraiso, Ind., a corporation of Indiana

Application September 29, 1949, Serial No. 118,605

2 Claims. (Cl. 272—66)

1

This invention relates to an improved diving board in which spring means supply the resiliency of the board.

One feature of this invention is the provision of an improved diving board structure having a substantially rigid diving board portion hinged to a base member with the necessary resiliency being supplied by a spring operatively connected to the diving board portion; another feature of the invention consists of housing the spring means under the diving board structure so that it may be readily shielded and will result in a compact structure; a further feature of the invention is the provision of easily adjustable spring means together with means for adjusting the spring means; still another feature of the invention is the provision of spring means for a diving board structure with the spring means being under a load in addition to that supplied by the diving board portion; a still further feature of the invention is the provision of spring means for a diving board structure wherein the spring means is adapted to be deflected substantially equal distances for unequal loads; and another feature of the invention is to provide a diving board structure formed in a compact unit with spring means an other moving parts under the board, and adapted to be contained in a side housing that is of substantially no greater width than the width of the diving board portion. Other features of the invention will become apparent in the detailed description of certain embodiments of the invention given hereinafter.

Various embodiments of the invention are shown in the accompanying drawings, of which: Fig. 1 is a plan view of one embodiment of the improved diving board structure; Fig. 2 is an elevational view of said structure; Fig. 3 is a vertical section taken along line 3—3 of Fig. 1; Fig. 4 is a horizontal section taken along line 4—4 of Fig. 3; Fig. 5 is a vertical section taken along line 5—5 of Fig. 3; Fig. 6 is a vertical section similar to Fig. 3 showing another embodiment of the invention; Fig. 7 is a horizontal section taken along line 7—7 of Fig. 6; Fig. 8 is a vertical section taken along line 8—8 of Fig. 6.

The improved diving board structure of this invention broadly comprises a movable diving board portion rotatably connected at one end to a base member, a member rigidly fastened to the movable portion on the bottom surface thereof, and a spring means operatively connected to said member to resist downward movement of the movable diving board portion.

The spring means is located beneath the diving

board portion. The diving board portion is made as rigid as can conveniently be done, and the resistance of the board to a load thereon is supplied by a spring means located beneath the board. An important factor in this invention is the provision of means whereby the spring will take unequal loads with substantially the same amount of deflection for each load. Thus the diving board structure will accommodate men, women, or children, of unequal weight.

In the embodiment shown in Figs. 1 to 5 inclusive, the diving board structure comprises an approach platform 20 constructed of an inverted channel member and supported at the rear by a post 21, a forward movable or diving board portion 22 projecting out over the edge 23 of a swimming pool, with the movable diving board being pivotally mounted at the front of the approach portion 20 on a cross-shaft 24. The movable diving board 22 is also made of an inverted channel member having cross bracing to make it as rigid as possible. Attached to the diving board 22 near the approach portion 20 are two depending and parallel substantially vertical arms 25. The shaft 24 passes through the top portions of these arms. Near the bottoms of these arms 25 there is located a vertical cross member 26, while spaced rearwardly from and substantially parallel to the cross member 26 there is located a stop member 27. This stop member extends between a pair of vertical, substantially parallel side housing members 28 arranged on either side of the diving board structure, and rigidly held by end members 29 and 30. The stop member 27 is held rigid by means of bracking members 31.

Between the cross member 26 and the stop member 27 there is located a conical compression spring 32. The small end of the spring 32 is located against the cross member 26 that extends between the arms 25. This small end is held by a pin 33 mounted on the cross member 26 and extending into the small end of the spring. The side housing members 28 serve to conceal the spring 32 and the arms 25, and these housing members are rigidly fastened to the edge of the pool by means of small angles 34. The housing members have a small cross shaft 36 near the top edges for supporting the front end of the approach portion 20.

By using a conical spring 32 to supply the resistance to deflection of the diving board portion 22 it has been found that no adjusting means is necessary for the spring. When a load is applied to the spring the large end compresses first, as it has a weaker resistance than the remainder of

the spring. Thus when a child uses the diving board the large end of the spring is compressed a certain distance before the remainder of the spring is deflected. When a heavier weight, such as that of a man, uses the board, the large end of the spring is also deflected first, with the remainder of the spring then being progressively deflected. Thus there need be no additional adjustment means for the conical spring, although such means may be provided if desired. The conical spring may be used with the auxiliary equipment shown and described in relation to the other embodiments of the invention.

The approach portion 20 and the diving board portion 22 are both covered by a continuous length of extensible padding 35, such as woven coconut fiber. This padding is freely stretchable, and is made with no break between the approach portion and the diving board.

In the embodiment shown in Figs. 6 to 8 an alternative type of spring means is shown. In this embodiment there are provided two concentric cylindrical springs with the outer spring 37 being larger and stronger than the inner spring 38. These springs extend between a cross member 26a and a backing plate 39. The backing plate is held in spaced relationship to a stop member 27a by means of threaded rods 40 passing through the stop member 27a and bearing against the backing plate 39. A small nut 41 is provided on each threaded rod 40 to lock it in position. The springs 37 and 38 are held in position by means of a plurality of horizontal rods 42 located adjacent the inner surface of the inner spring 38 and extending from the stop member 27a through the backing plate 39 and the cross member 26a. The backing member 39 and the cross member 26a are slideable on these rods. A center rod 43 is also provided extending through the center of the concentric springs 37 and 38, with this rod also extending from the stop member 27a through the backing plate 39 and cross member 26a. This center rod is welded or otherwise fastened to the cross member 26a, and is slideable with respect to the backing plate 39 and the stop member 27a. The end extending through the stop member is threaded and provided with a nut 44. By means of this rod initial compression may be applied to the springs 37 and 38 in addition to that provided by the weight of the diving board portion 22. The nut 44, which is adjustable, serves to limit expansion of the springs, and serves as a stop when load is suddenly released from the diving board portion.

The resistance of the springs 37 and 38 may be adjusted by moving the backing plate 39 to various distances away from the stop member 27a. Thus when there is a children's day at the pool the springs may be adjusted so that they are under very little or no initial compression. On other days when men use the pool, the springs may be placed under relatively great compression. If desired, the smaller inner spring 38 may be made so that it has a greater length than the larger

outer spring 37, when no loads are on the springs. Then by spacing the cross member 26a and the backing plate 39 a distance apart greater than the length of the outer spring 37 the inner spring 38 will be the only one that will resist load on the diving board 22. With this arrangement the outer spring 37 will not come into play until the inner spring 38 has been compressed under the load for such a distance that its resulting length is equal to the length of the outer spring 37. Although as shown, the inner spring 38 is the weaker spring, it may be desirable in some cases to make the outer spring 37 the weaker one.

This invention is related to that shown in my Patent No. 2,590,563 granted March 25, 1952.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. In a diving board, an approach board, a diving board of channel shape having its flanges downwardly directed, a supporting structure comprising parallel walls encompassing the sides of said diving board, a shaft extending thru said walls and said flanges for pivotally supporting said diving board, opposed brackets secured to said flanges, said shaft extending thru said brackets, a cross member secured to the lower portion of said brackets, a transverse stop member secured to said walls rearwardly of said cross member, and a conical volute spring between said members with the larger end against the stop member.

2. In a diving board, a housing having spaced walls, a channel shaped diving board having its flanges downwardly directed and positioned between said walls, a pivot shaft extending thru said walls and flanges for supporting said board, a pair of opposed brackets secured to said flanges, a cross member attached to the lower portion of said brackets, a stop member extending between said walls, and yielding means extending between said cross member and said stop member, said yielding means having a low initial resistance constantly increasing to a higher resistance as said yielding means is contracted.
